UNITED STATES PATENT OFFICE.

JOSEPH ROMINE SMITH, OF BROCKVILLE, ONTARIO, CANADA.

BOLT-CUTTER.

SPECIFICATION forming part of Letters Patent No. 361,554, dated April 19, 1887.

Application filed August 10, 1886. Serial No. 210,573. (Model.)

To all whom it may concern:

Be it known that I, JOSEPH ROMINE SMITH, a citizen of the United States, residing at Brockville, in the county of Leeds and Province of Ontario, Canada, have invented certain new and useful Improvements in Bolt-Cutters; and I do declare the following to be a full, clear, and exact description of the invention, such as will enable others skilled in the art to 5 to which it appertains to make and use the same, reference being had to the accompanying drawings, and to letters or figures of reference marked thereon, which form a part of this specification.

15 Figure 1 of the drawings is a representation of a front elevation. Fig. 2 is a similar view with the strap removed. Fig. 3 is a transverse section on the line $\alpha\alpha$, Fig. 1. Fig. 4 is a bottom view of the tie-plate. Fig. 5 is a detail section, and Fig. 6 is a detail view.

My invention relates to bolt-clippers for severing bolts; and it consists in the construction and novel combination of parts, as herein-after described, and pointed out in the claims.

25 Referring by letter to the accompanying drawings, A B designate the cutting levers or blades of the bolt-clipper, said blades being provided at their upper ends, along their inner edges, with the beveled cutting-edges C D.

30 The blades A B are provided near their upper ends with circular seats E E, in which are placed the eccentric bearing-rings G H, said rings G H being held to their adjustments by set-screws I J, introduced from the back edges of said cutting levers or shears A B, and extending into the seats E E in said shears, and bearing against the rings G H, for said purpose.

The eccentric bearing-rings G H are provided in one of their sides with a recess, Z, 40 for the purpose of receiving one end of a rod or other suitable device, whereby the said rings may be turned and adjusted, as will be presently explained. In practice I employ a wrench for turning these rings, which consists 45 simply of a lever having an eye in one end to pass over the bolts, and has a stud or fixed pin on one side to enter the recesses Z of the rings; but it is obvious that a plain round rod may be used for this purpose.

50 K designates a tie-plate, which is provided with threaded bolts L M, which project vertically from the face of said tie-plate K.

The tie-plate K is provided with holes a b near its ends, in which holes a b the lower or unthreaded ends of the bolts L M are seated, 55 in the following manner: The bolts L M are provided near their lower ends each with an annular external groove, which grooved portions are placed in the holes a b in the tie-plate after the latter has been heated to expand it. 60 The tie-plate is then cooled, and as it cools it shrinks, and the material of said tie-plate enters the annular grooves N in the bolts L M, and secures said bolts L M firmly in their seats in said tie-plates. 65

The cutting-levers A B are pivoted at their lower ends in bearing-seats in the upper ends of the power-levers P Q, said levers P Q being pivoted together upon the guide-pin R, provided in its head with a seat, S, made transversely through it, through which seat S the stem of the T-strap T passes and works when the bolt-clipper is operated. The upper end of the T-strap T is provided near its ends with bolt-holes, through which the threaded ends 70 of the bolts L M project, and nuts U V are screwed upon the threaded ends of said bolts to secure the tie-plate and T-strap in place. 75

In adjusting my bolt-clipper I remove the nuts on the screw-bolts L M and lift off the T-strap T, at the same time lifting the guide pin or stud R from its seat, thus disclosing the eccentric in each cutter or blade. By loosening the set-screws I J the eccentric-rings G H may be revolved on the screw-bolts L M by 80 a rod or wrench placed in the recesses Z, as above described, until the cutters are properly adjusted, when the set-screws I J are again tightened and the T-strap replaced. The T-strap prevents oblique motion of the cutters 85 with reference to their operating-levers, owing to the fact that the stem of the T-strap extends at right angles to the strap-head, and maintains said position at all times when the parts are secured together and are operated by 90 said stem of the T-strap moving in the guide-pin. 95

I claim—

1. As an improved article of manufacture, a bolt-cutter comprising two pivoted cutting-jaws, two pivoted hand-levers, a strap connecting the cutting-jaws, cam-rings surrounding the connecting-bolts of the strap, and an integral arm of the strap passing through an 100

eye in the connecting-bolt of the hand-levers, substantially as specified.

2. As an improved article of manufacture, a bolt-cutter comprising two pivoted hand-levers, a T-plate connecting the cutting-jaws by bolts, with its longer branch extending through an eye in the connecting-bolt of the hand-levers, cam-rings surrounding the bolts of the connecting-plates, and set-screws for

holding the said rings in their adjusted positions, substantially as specified.

In testimony whereof I affix my signature in presence of two witnesses.

JOSEPH ROMINE SMITH.
